UNITED STATES PATENT OFFICE.

HARRY D. LATHROP AND WALTER H. PAULSON, OF CHICAGO, ILLINOIS.

MILK-CAN-WASHING MACHINE.

1,172,808.

Specification of Letters Patent. Patented Feb. 22, 1916.

Application filed March 31, 1915. Serial No. 18,235.

To all whom it may concern:

Be it known that we, HARRY D. LATHROP and WALTER H. PAULSON, citizens of the United States, and residents of the city of Chicago, county of Cook, and State of Illinois, have jointly invented certain new and useful Improvements in Milk-Can-Washing Machines, of which the following is a specification.

10 Our invention relates to improvements in can washing machines especially designed for use in the washing and sterilizing of milk cans and more specifically to improvements in the can reversing mechanism used 15 in connection with this class of machines.

The object of our invention is the production of a can reversing mechanism of this character which will be of durable and economical construction, and one which will 20 be highly efficient in operation.

Other objects will appear hereinafter.

With these objects in view, the invention consists in the combinations and arrangements of parts hereinafter described and 25 claimed.

The invention will be best understood by reference to the accompanying drawings forming a part of this specification, and in which,

30 Figure 1 is a side elevation of the discharge end of a can washing machine equipped with reversing mechanism embodying the invention, Fig. 2 is a vertical longitudinal section of a portion of the construction shown in Fig. 1, illustrating the manner of reversing of a can, and Fig. 3 is an enlarged detail section taken on line y—y of Fig. 2.

The preferred form of construction, as illustrated in the drawings, comprises a can reversing mechanism which is especially designed for use in connection with a machine adapted for the washing of milk cans and the covers therefor. Said machine comprises guides 42, as shown in Fig. 2, upon which the milk cans A are adapted to be slid in inverted position, the latter, in the movement of the same along said guides being thoroughly washed and sterilized.

45 The washing and sterilizing mechanism is not shown in the present application, inasmuch as the same forms no part of the subject matter of this application which is directed only to mechanism through the medium of which the milk cans, after being

washed and sterilized are inverted to upright position for discharge from the machine. This can reversing mechanism which is arranged at the discharge ends of the guides 42 comprises a substantially semi-circular frame 43 which is pivoted or trunnioned at 44 to the upper ends of posts 45, preferably of a vertical adjustable construction. The pivots or trunnions 44 are located intermediate the ends of the frame 43 and adjacent the longitudinal edges thereof but in such a position that said frame is adapted normally of its own weight to assume a position shown in Fig. 1, that is one in which the same will be adapted to receive a can discharged from the guides 2, the can, in being discharged from said guides, being adapted to drop into said frame, as clearly shown in Fig. 1. Said frame is formed to conform with the shape of the can, the semi-circular body thereof engaging with the body of the can and the lower end thereof being formed for engagement with the neck of the can. Upon the deposit of the can onto said frame 43, the weight of the can will cause said frame to swing upon its pivots or trunnions 44 to the position shown in Fig. 2 thereby accomplishing the reversing of the can or rocking of the same to upright position. The frame 43 will deposit the can onto inclined discharge guides 46 between which is arranged a reinforcing medial channel 47.

In order to break the fall of the can, in the deposit thereof onto the guides 46 so as to insure against toppling of the can, as might otherwise result from too sudden jar, a cushioning device in the form of a plate 48, is provided which is pivoted at 49. A weight 50 co-operates with said plate to normally hold the same in an elevated position, as shown in Fig. 1, a chain 51 serving to limit the downward movement of the weight. With this arrangement, in the reversing of the can, and deposit thereof onto the guides 46, the outer or forward edge of the lower end of the can will contact with the plate 48, the latter, under the weight of the can, yielding downwardly with the result of very gently settling the can to position on the guides 46. A roller 52 is provided on the frame 43 for engagement with the rearward edge of the lower end of the can in order to prevent relative longitudinal sliding of the can in the dis-

charge thereof from said frame, said roller at the same time insuring against any retention of the can through friction, as might otherwise result. Upon the release 5 of the can from the frame 43, the latter, of its own weight, will automatically return to initial position for the reception of the succeeding can, the location of the trunnions or pivots 44, as shown and above mentioned, 10 and the balancing of the frame between supports 45, insuring positively the automatic swinging of said frame to its first position.

The guides 46 are inclined, as shown, at 15 such an angle that the cans deposited thereon will slide downwardly by gravity and be discharged from the lower ends of said guides. The guides 46 are pivotally mounted as at 46' in order to permit of adjustment 20 of the angularity thereof to secure the desired rapidity of movement of the cans thereon.

While we have illustrated and described the preferred form of construction for carrying our invention into effect, this is capable of variation and modification without departing from the spirit of the invention. We, therefore, do not wish to be limited to the precise details of construction set forth, 30 but desire to avail ourselves of such variations and modifications as come within the scope of the appended claims.

Having described our invention what we claim as new and desire to secure by Letters 35 Patent is:

1. In a device of the class described, the combination of a guide; and an oscillatory member the axis of oscillation of which is located intermediate its ends, said member 40 being arranged for coöperation with said guide and adapted, upon the deposit of a can thereon, from said guide, to be automatically oscillated by the weight of the can, to reverse the can, and said member being 45 adapted by gravity to automatically return to initial position after the release of a can therefrom, substantially as described.

2. In a device of the class described, the combination of a guide; and an oscillatory 50 member substantially semi-cylindrical in form, the axis of oscillation of which is located intermediate its ends and adjacent the longitudinal edges of said member, said member being arranged for coöperation 55 with said guide to receive a can deposited thereon from said guide and automatically oscillate by the weight of the can, to reverse the latter, and said member being adapted, by gravity, to automatically return to initial 60 position after the release of a can therefrom, substantially as described.

3. In a device of the class described, the combination of a guide; can reversing means arranged for coöperation with said 65 guide, said means comprising a substantially

semi-cylindrical member; and outwardly projecting trunnions on said member intermediate the ends thereof and adjacent the longitudinal edges of said member swingingly supporting the latter, said member being adapted to receive a can deposited thereon from said guide and automatically oscillate by the weight of the can, to reverse the latter, and said member being adapted, by gravity, to automatically return to initial 75 position after the release of a can therefrom, substantially as described.

4. In a device of the class described, a main can guide; a can discharge guide; means adapted, upon the deposit of a can 80 thereon from said main guide, to reverse the can and deposit the same on said discharge guide; and a cushioning device with which the can is adapted to contact in the deposit of the same on said discharge guide, substantially as described.

5. In a device of the class described, a main can guide; a can discharge guide; means adapted, upon the deposit of a can 85 thereon from said main guide, to reverse the can and deposit the same on said discharge guide; and a cushioning device with which the can is adapted to contact in the deposit of the same on said discharge guide, said cushioning device comprising a normally 90 elevated member adapted to yield downwardly upon engagement of a can therewith, substantially as described.

6. In a device of the class described, a main can guide; a can discharge guide; 100 means adapted upon the deposit of a can thereon from said main guide to reverse the can and deposit the same on said discharge guide; and a cushioning device adapted for engagement with the front edge of the lower end of the can in the deposit thereof on said discharge guide, substantially as described.

7. In a device of the class described, a main can guide; a can discharge guide; means adapted upon the deposit of a can 110 thereon from said main guide to reverse the can and deposit the same on said discharge guide; and a cushioning device adapted for engagement with the front edge of the lower end of the can in the deposit thereof on said discharge guide, said cushioning device comprising a pivotally mounted normally elevated member adapted to yield downwardly upon engagement of the can therewith, substantially as described.

8. In a device of the class described, a main can guide; an inclined can discharge guide; means adapted upon the deposit of a can thereon from said main guide to reverse the can and deposit the same on said discharge guide; and a pivotally mounted normally elevated plate arranged above said discharge guide adapted for engagement with the front edge of the lower end of a can in the deposit thereof onto said dis- 125

charge guide, said plate being adapted to yield downwardly to substantially the plane of said discharge guide under the weight of the can, substantially as described.

- 5 9. In a device of the class described, a can guide; a pivotally mounted frame adapted upon the deposit of a can thereon from said guide to reverse the can; and a roller at the lower end of said frame, when the latter is
10 in reversed position, for engagement with

the rearward edge of the corresponding end of the can, substantially as described.

In testimony whereof we have signed our names to this specification in the presence of two subscribing witnesses.
